TOY HELICOPTER

Bruno Nagler, New York, N. Y.

Application October 1, 1951, Serial No. 16,805

Term of patent 14 years

(Cl. D34—15)

To all whom it may concern:

Be it known that I, Bruno Nagler, a citizen of the Republic of Austria, and a resident of New York city, New York, have invented a new, original, and ornamental Design for a Toy Helicopter, of which the following is a specification, reference being to the accompanying drawing, forming part hereof.

Fig. 1 is a perspective view of a toy helicopter, showing my new design;

Fig. 2 is a top plan view thereof;

Fig. 3 is a front elevational view thereof; and

Fig. 4 is a rear elevational view thereof.

The drawing figures are lined to indicate sec-

tions which are transparent or give the appearance of being transparent.

I claim:

The ornamental design for a toy helicopter, as shown and described.

BRUNO NAGLER.
